A. B. EVANS

SHEET GRIPPING MECHANISM OF PRINTING MACHINES

Filed Nov. 26, 1924

Inventor
A. B. Evans:
by
W. S. SWART:
Attorney.

UNITED STATES PATENT OFFICE.

ARTHUR BURROUGHS EVANS, OF LEEDS, ENGLAND.

SHEET-GRIPPING MECHANISM OF PRINTING MACHINES.

Application filed November 26, 1924. Serial No. 732,378.

To all whom it may concern:

Be it known that I, ARTHUR BURROUGHS EVANS, a subject of the King of Great Britain and Ireland, residing at 7 Woodland Grove, Leeds, England, have invented certain new and useful Improvements in Sheet-Gripping Mechanism of Printing Machines, of which the following is a specification:

10 This invention relates to sheet fed printing machines of the kind in which the sheet is held to the sheet carrying cylinders, chains or reciprocating carriages or the like by means of grippers which nip the front 15 edge of the sheets and hold them upon gripping bars or pads or the like fitted to and moving with the sheet carrying cylinders, chains or reciprocating carriages or the like, or hold them to the leading edge 20 of the sheet carrying cylinders where no bars, pads or the like are provided. It is customary in such machines for a number of these grippers, each consisting of a single element, to be carried in spaced relation 25 upon a shaft which extends across the sheet, each individual gripper being capable of angular adjustment on this shaft so that all the grippers may be adjusted to act with equal or uniform gripping pressure upon 30 the sheet.

The present invention has for its object to overcome the difficulty which is experienced in attaining and maintaining this uniform gripping pressure of the individual grippers, whether the grip be secured by positive or spring actuation of the shaft, owing to the delicacy of the required adjustment.

According to the present invention each 40 individual gripper comprises two parts, one of which, forming the gripper proper, is rotatably mounted upon the gripper carrying shaft whilst the other is secured adjustably upon the said shaft and is adapted 45 upon partial rotation of the shaft, to move the gripper proper from the gripping position in which it is maintained by a spring the strength of which corresponds to the pressure which the gripper is required to exert, which spring is so positioned that the force which it exerts to maintain the gripper proper in the gripping position is relaxed when the gripper proper is moved from the 50 said position.

According to the invention, moreover, the spring is advantageously connected between

the two parts of the gripper. It may, however, be otherwise mounted so long as it acts upon the gripper proper and is anchored in fixed relation to the gripper carrying 60 shaft.

When the grippers provided according to the invention have been adjusted they will maintain a uniform and equal pressure upon the sheets presented to them notwithstanding variations in thickness or widths of the sheets to be printed, or accidents of 65 printing.

The invention is hereinafter described, by way of example, with reference to the accompanying drawings in which

Fig. 1 is a side elevation of a gripper having a flat spring, the gripper being shown in section;

Fig. 2 is a similar view of a gripper having a different form and arrangement of spring;

Fig. 3 is a similar view of a gripper showing another spring arrangement; and,

Fig. 4 is a rear elevation of a gripper 80 with a spring coiled about the gripper shaft.

In carrying the invention into effect as illustrated in Figure 1, one part *a* of the gripper comprises a sleeve *a*¹ adapted to be received upon the shaft *b* and to be secured thereto by means of a clamping screw *a*² or like device adapted to cause a die *a*³ to grip the shaft *b*. The other part *c* comprises the gripper proper in the form of a finger *c*¹ of the usual construction, the rear portion of which is bifurcated and formed into two eyes *c*² or sleeves adapted to fit upon the shaft *b* rotatably and to be positioned one on each side of the sleeve *a*¹. The sleeve *a*¹ is provided at a suitable position 95 on its periphery with a projection *a*⁴ adapted to contact with the lower face *c*³ of the finger *c*¹ and thus to lift the finger *c*¹ on rotation of the shaft *b* and at the same time to limit the forward rotational movement of 100 the part *c* with reference to the part *a*, which movement results from the action of a flat spring *d* mounted upon a boss *a*⁵ of the part *a* by means of a screw *a*⁶, the spring being adapted to engage at its extremity with the upper face *c*⁴ of the finger *c*¹.

In the construction illustrated in Figure 2, the main parts *a* and *c* are arranged as in the construction represented in Figure 1 but the flat spring *d* is replaced by a helical spring *e* connected at one end to a lug *a*⁷

on the part *a*, which lug is advantageously in a position oppositely disposed with reference to the projection *a*³, and at the other end to a lug *c*⁵ upon the under face *c*³ of the finger *c*¹, the helical spring *e* being disposed in such manner that it is in tension.

In the construction shown in Figure 3, a helical spring *f* is mounted, in such manner as to be in compression upon and between 10 two oppositely disposed lugs *a*⁷ *c*⁶, provided respectively upon the part *a* and upon the upper face *c*⁴ of the finger *c*¹.

With reference to Figure 4 the main parts *a* and *c* are provided as hereinbefore described but a helical torsion spring *g* is used, which spring *g* is mounted loosely upon the shaft *b* in position adjacent one eye *c*² of the part *c*, one end of the spring *g* being bent parallel with the shaft *b* so as to engage within a hole *c*⁷ in the eye *c*² and the other end being likewise provided for engagement within a hole *h*² in a collar *h* mounted upon the shaft *b* and fixed thereto by means of a pin *h*¹ or other suitable device. The spring *g* is of such form that the finger *c*¹ of the part *c* tends to press against the projection *a*³ of the part *a*.

In order to set a compound gripper provided according to the invention, the shaft *b* is moved to the position it occupies when the gripper is closed, the screw *a*² or like device is loosened so that the die *a*⁸ ceases to grip the shaft *b*, the finger *c*¹ of the

gripper proper *c* is closed upon the sheet 35 after insertion of a thin piece of material 35 at the point of contact of the projection *a*³ with the under face *c*³ of the finger *c*¹ and the screw *a*² or like device is tightened so that the die *a*⁸ again grips the shaft *b* while it is still in the position before referred to. 40

The thin piece of material is then removed from between the projection *a*³ and the lower face *c*³ of the finger *c*¹, the finger *c*¹ thus being allowed to press freely upon the sheet under the action of the spring 45 the strength of which corresponds to the gripping pressure.

I claim:

1. Sheet gripping means for printing presses comprising a rock shaft, a gripping finger loosely mounted on said shaft, a collar adjustably secured to the shaft and having a part projecting beneath said finger and forming a stop for the same, and a spring normally holding the finger against 50 said stop.

2. Sheet gripping means for printing presses comprising a rock shaft, a gripping finger loosely mounted on said shaft, a collar adjustably secured to the shaft and having a part projecting beneath said finger and forming a stop for the same, and a spring interposed between the collar and finger and normally holding the finger against 55 said stop.

ARTHUR BURROUGHES EVANS
